Inventor:
Walter S. Walker

UNITED STATES PATENT OFFICE

2,276,551

TERRACING MACHINE

Walter S. Walker, Helena, Mo.

Application February 10, 1938, Serial No. 255,782

1 Claim. (Cl. 37—153)

My invention relates to improvements in implements which are used for terracing the sides of hills to break the force of water coming from heavy rains, making drainage ditches and terracing the sides of roads.

Further objects are to so construct an implement, that by its use, dirt may be moved either to the right or left side of the machine as desired, and may be adjusted for so doing with the utmost ease; also to provide ready means whereby the terracing blade may be lifted from the surface of the ground, and also may be adjusted at any angle of inclination for moving dirt in the process of terracing and making drainage ditches. Still further objects are to construct a terracing machine that shall be simple, substantial, durable, light in weight, cheap in cost of manufacture and also be easy to pull.

I attain these objects by the machine illustrated in the accompanying drawing in which Figure 1 is a perspective view of the terracing machine.

Figure 2 is a perspective view of a device to be attached to either side of the machine shown in Figure 1 for the purpose of preventing the machine sliding side-ways on steep surfaces.

Figure 3 is an enlarged view of a cog device shown in Figure 1 on line A—A.

Figure 4 is a horizontal cross-section view on the line B—B Figure 1.

Figure 5 is an enlarged view of ratchet segment 14'' and tilting lever 14 shown in Figure 1.

Figure 6 is an enlarged view of the front portion of the machine frame.

Referring to Figure 1, terracing blade 1 is made of steel with a sharp edge next to the ground. Each end of said blade 1 is pivotally connected at 2 to a pivot block 3 rotatably mounted on the lower end of standard 4. The bolt 5 pivotally secures the lower end of standard 4 to the front end of blade carrier 6. The blade carrier 6 is pivotally connected to side bar 1' at and in front of transporting wheel 8, which is rotatably mounted as shown in Figure 4. Said wheel is secured in place by bolt 8' which passes through fork side 9' and secured on the front end portion of outer runner 9 in Figure 4.

Referring to the upright standard 4 in Fig. 1 extending from 8' to 13', cog device AA, curved beam 13, standard 4, and crank 12 shown in Figure 1, it will be seen that the lifting crank 12 is revolvably mounted on the curved beam at 11'' and on the upright standard at 12'. A cog device (Fig. 3) is provided by means of which the

standard 4 is raised or lowered by turning crank 12. This combination of parts raises or lowers the terracing blade 1 in Fig. 1 to which it is attached. A similar device is provided for raising or lowering the other end of the terracing blade.

Referring to Figure 1, the curved beam 39 is pivotally connected by a clevis 21' to the upper end of standard 22. The power to pull said machine is attached at 41 by reason of the curvature of beam 39 the motive power pulls downward and forward thereby forcing the terracing blade 1 downward and into the ground, which together with the weight of the machine furnishes the power to force the terrace blade into the ground, and does away with the necessity of building a heavy machine. The auxiliary curved beam 13 and corresponding one on the opposite side of the machine together with the brace bars 10, 20 and 24' brace the frame of the machine. The curved beam 39 is further braced by two chains attached to the double tree at 40' and 42 and extending rearwardly and attached at the top of standard 4 and to the corresponding standard on the opposite sides of the machine.

Referring to Figure 2, this is a device to prevent the terracing machine sliding sideways on sloping ground. It consists of a runner 36, a bar 34 with holes at 33 and connecting braces 37. This device may be attached on either side of the base of the machine by bolting 33 (Figure 2) to 32 (Figure 1), and hook 35' (Figure 2) in link 35'' (Figure 1); and when so attached the runner 36 runs in the bottom of low places and prevents the machine from sliding sideways.

Hook 23' pivotally mounted on central bar when placed in a selective aperture of crossbar 31' advances one side of base bar 1' and shifts the terracing blade into various oblique positions by putting hook in the different holes of cross-bar 31'.

The cross-bars 31, 31', 31'', 20 and 10 are all pivotally connected at their ends by reason of which hook 23' can be put into any of the holes in cross-bar 31'.

Referring to Figure 1, the ratchet segment 14'', lever 14, and rod 15 connected to the lower end of lever 14, constitute an actuating means for cross-bar 17; the latter sliding back and forth by means of a slot mounting in the top central beam 26, as lever 14 is moved back and forth. The ends of cross-bar 17 are connected to rods extending to pivot connections 19 at opposite ends of the terrace blade 1. This construction permits movement of the terrace blade 1.

There are four wheels on this machine marked

8 and 28 and corresponding wheels on the opposite side of the base for the purpose of moving the machine.

Figure 4 shows that the wheels are solid rollers with four discs attached to the outer side of said rollers. As said discs extend above the rollers, therefore the discs cut into the ground and prevent the machine from sliding sideways.

In operation, the operator hitches the motive power—not shown—to double tree 41, tilts the top of terracing blade 1 either backward or forward by lever 14, raises or lowers the terracing blade 1 by means of crank 12 and corresponding crank on the opposite side of the machine. The hook 23' is placed into the holes in bar 31' for the purpose of giving the terrace blade 1 the desired position in order to move dirt either to the right or left side of the machine. The double tree 41 is held in position by chain 43, and seat 27 is on the rear part of the machine.

Having fully described by invention what I claim as new and desire to secure by Letters Patent is:

In a machine of the class described the combination of a horizontal base frame, a terracing blade supported for adjustment at the front of the frame, vertical standards fixedly supported at the forward portion of the base frame, upright adjustable blade supports located between the vertical standards and the terracing blade, means 5 pivotally connecting the blade to said supports for tilting movement thereof about a horizontal axis, an operating lever mounted upon the base frame, mechanism operatively connecting said lever with said blade for effecting a tilting adjustment of the blade about its horizontal mounting axis, upper and lower link members supporting said blade supports for vertical adjustment and having pivotal connection respectively with the vertical standards and with the base frame, actuating means including rack and pinion mechanism operatively connected with the blade 10 supports and the vertical standards for effecting a vertical adjustment of the blade.

WALTER S. WALKER.
